UNITED STATES PATENT OFFICE

2,132,750

JIG

Ernst F. Muller, Columbus, Ohio, assignor to
The Jeffrey Manufacturing Company, a corpora-
tion of Ohio

Application November 27, 1936, Serial No. 113,029

3 Claims. (Cl. 209—504)

This invention relates to a jig, and particularly to a jig for washing coal and separating the refuse found in raw coal from the clean coal.

An object of the invention is to provide an improved diaphragm type of jig in which the water in the jig tank exerts a static force on the jig diaphragm and in which compressed air means are provided to counteract this static force, means also being provided to reciprocate or oscillate the diaphragm by positive motion in reverse directions.

Other objects of the invention will appear hereinafter, the novel features and combinations being set forth in the appended claims.

In the accompanying drawings,

Fig. 1 is a side elevational view of the jig comprising my invention;

Fig. 2 is a side elevational view of the device with one compartment shown in section; and

Fig. 3 is an enlarged detail elevational sectional view showing particularly the operating means for the diaphragm and the compressed air means which counteracts the static load thereon.

The jig comprising my invention comprises a main frame 10 formed by longitudinal and transversely extending bottom channels 11 and upwardly extending angle members 12. Upon the main frame 10 is supported a tank 13 provided with two compartments 14 and 15. The compartments 14 and 15 will be of similar construction except for obvious differences which are principally that the compartment 14 is provided with a feed chute 16 and the compartment 15 is provided with a discharge chute 17. Within each of said compartments 14 and 15 is a perforate material supporting plate or screen 18, pivoted at its forward end on a transverse rod 19 and mounted upon adjustable hangers 20 at its rear end. The screen or plate 18 will provide a support for the material undergoing a jiggling operation.

Positioned below the plate 18 is the bottom of the compartment 14 or 15 which comprises a disc-shaped diaphragm 21, the cylindrical periphery of which is attached to the tank walls by a flexible ring 22 preferably made of fabricated rubber. Said ring 22 will permit reciprocatory motion of the diaphragm 21 for the purpose of causing water in the tank 13 to move cyclically up and down through screen 18.

Rigidly attached to a center casting 23 forming part of the diaphragm 21 is a piston rod 24 carrying at its lower end a piston 25 (Fig. 3) which reciprocates in a cylinder 26. The cylinder 26 has a large opening 27 to provide atmospheric

pressure to the top side of piston 25. It also has a top journaled sleeve 28 which with piston 25 insures straight line motion of rod 24 and diaphragm 21. The head end of cylinder 26 is provided with a head 29 and is attached to a pressure air line 30 which applies pressure to the lower side of the piston 25 to balance or counteract the weight of the load on the diaphragm 21. The air line 30 extends to a compressed air tank 31 in which air is automatically maintained at a substantially constant pressure by automatically operable pressure responsive motor and compressor mechanism 32, of any well-known construction. As a consequence the energy required to reciprocate the diaphragm 21 is greatly reduced.

The cylinder 26 is preferably mounted between a pair of channel members 33 which are rigidly attached to the main frame 10.

To provide for reciprocation of the diaphragm 21 I provide a pitman 34 pivotally attached to the piston rod 24 and to a slide block 35 slidably adjustable on a pivoted walking beam 36, which beam 36 is, in turn, pivotally attached to a bracket 37 carried by the channel members 33.

The walking beam 36 carries a roller 38 which rides between upper and lower cam surfaces 39 and 40, respectively, of a cam 41. Cam 41 is mounted upon a transversely extending shaft 42 supported upon the main frame 10 by appropriate journal bearings, one of which is seen at 43. It will be evident that there will be two of said cams 41 and shafts 42, and said shafts 42 are connected together by appropriate chain and sprocket mechanism 44. One of said shafts 42 is driven directly from an electric motor 45, and the other is driven from the first shaft 42 through the chain and sprocket mechanism 44.

It is preferred that the diaphragms 21 in the two compartments 14 and 15 be adjusted to operate 180 degrees out of phase thereby to equalize the load on the motor 45. However, any other adjustment may be made, and if desired, they may be operated in phase.

It is to be particularly noted that since the pressure applied to piston 25 is substantially constant the upward force on diaphragm 21 will be substantially constant and thus always balance the static downward force thereon due to the weight of water in compartment 14 or 15. This upward force may even be greater than the static downward force to aid in balancing part of the dynamic downward force on said diaphragm. It is for this reason that cam 41 is a double cam and is provided with both upper and

lower cam surfaces 39 and 40 which insure uniform cyclic movement of diaphragm 21 by a positive action in both directions.

It will be evident that adjustment of the slide 5 block 34 on the walking beam 36 will adjust the stroke of the diaphragm 21 during each cycle of operation. Said slide block 34 may be locked in any adjusted position by a wedge 48.

To supply the jigging water to the two compartments 14 and 15 I provide a longitudinally extending water pipe 47 with individual lead pipes 48, one for each of said compartments 14 and 15.

Each of said compartments 14 and 15 is also provided with a weir 49 having a vertical adjustable bottom plate 50 to adjust the size of an opening 51 leading to a refuse discharge chute 52 formed by a stationary plate 53 and a pivoted plate 54 and leading to a refuse discharge boot 55. Pivoted plate 54 is rigidly attached to an arcuate wear plate 56 to the bottom of which is attached a pivoted weight 57. The plate 53 is also arcuate opposite the plate 56. Between the plates 53 and 56 is a paddle wheel type of discharge valve 58 which controls the rate of discharge of refuse into the boot 55.

To provide for uniform conditions of treatment of the coal, thereby to insure a thorough cleaning thereof, I provide automatic float responsive control mechanism for each of the valves 58 which maintains a bed of refuse on the plate 18 at a uniform depth. Said float control mechanism comprises a float 59 of the totally submerged type carried on a parallel motion link mechanism 60, and controls a rod 61 pivotally attached to a shield mechanism 62, which controls variably the angular rotation of a ratchet wheel 63 which is operated by a pawl 64 carried by a constantly reciprocating bell crank lever 65 which is reciprocated by the shaft 42 by an appropriate rod 66 and a crank mechanism 67. It is thus evident that the angular rotation in step-by-step fashion of the valve 58 for each reciprocation of the bell crank lever 65 will be determined by the position of the float 59. This will insure the maintenance of a bed of refuse of substantially constant depth on the perforate plate or screen 18.

To remove the refuse from the boots 55 of the two compartments 14 and 15, bucket type elevator mechanisms 70 are provided in association with each of said boots 55, which elevator mechanisms 70 are driven from a motor 71.

To provide access to the compartments 14 and 15 below the screens or perforate plates 18 each of said compartments 14 and 15 is provided with a removable door 72.

The jig comprising my invention is particularly adapted for use to clean coal and to separate the refuse found in raw coal such as shale, pyrite and bony coal, but it may be employed to concentrate ores.

In the operation of the device, particularly in the cleaning of coal, the run of mine coal will be fed to the feed chute 16 and formed in a bed on the screen or perforate plate 18 where it will be subjected to the periodic pulsations of water passing upwardly and downwardly through said screen 18. This action will effect a stratification of the bed according to specific gravity with the high gravity refuse stratified on the bottom of the bed and the low and intermediate gravity refuse stratified thereabove. The coal will, of course, have the lowest specific gravity of the material forming the bed.

The float 59 is not a true float in that it is entirely below the liquid level in the tank 13, but it effectively stratifies as a piece of coal on top of the refuse bed. Said float 59 will be effective to maintain the refuse bed at a predetermined depth on the screen 18 by virtue of its control of the valve 58, as previously described.

The highest gravity refuse will be separated in the compartment 14 and discharged into the boot 55 thereof. The coal and intermediate gravity refuse, such as bony coal, and possibly small particles of shale, will pass over the weir 14 into the compartment 15 where they will be subjected to a second jigging action. In said compartment 15 the refuse will again form in the lower strata on the screen 18 and will be maintained at a substantially constant depth by the float 59 and valve 58 of said compartment 15. Only the clean coal will pass over the discharge chute 17, the intermediate gravity refuse being withdrawn by said valve 58 and discharged into boot 55 of said compartment 15.

It will be evident that the jigging water in the compartments 14 and 15 of tank 13 will have a downward thrust on the diaphragms 21. The static thrust will, of course, be proportional to the weight of the liquid in the compartment and this force may be counteracted entirely or partially by the air pressure acting upon the bottom of the piston 25. As this air pressure will be substantially constant the counteracting force will also be substantially constant regardless of the position of the diaphragm 21. If desired, the counteracting force may even be greater than the static force, because there will, of course, be a dynamic force necessary to move the liquid upwardly through the screen 18, and this counteracting force may, at least in part, aid in reducing the work necessary to perform this lifting operation of the water.

In order to insure the accurate movement of the diaphragm 21 in accordance with a predetermined time-velocity curve, the double cam 41, with parallel upper and lower cam surfaces 39 and 40, is provided which controls movement of the diaphragm 21 in both directions by a positive action by virtue of the roller 38 having a diameter substantially equal to the spacing between the cam surfaces 39 and 40. Thus, the fluid pressure counteracting means may be employed to counteract not only the static force on the diaphragm 21, but also to counteract at least part of the dynamic force. This reduces appreciably the amount of work the electric motor 45 must do to effect the jigging operation.

As was previously mentioned, it is also desirable to operate the two diaphragms 21, 21 180 degrees out of phase which will further equalize the load on the motor 45. If desired, however, said diaphragms 21, 21 may be operated in phase.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. In a jig, the combination with a tank adapted to hold water, a screen in said tank, a diaphragm in the bottom of said tank and below said screen, means for reciprocating said dia-

- phragm to cause liquid in said tank to move through said screen cyclically, means for guiding said diaphragm in a parallel motion and for counteracting the downward force of said water on said diaphragm comprising a cylinder, a piston in said cylinder, a piston rod rigidly attached at its top to said diaphragm and attached at its bottom to said piston, a guide for said piston rod, and means for applying a fluid pressure to said piston.
- 5 2. In a jig, the combination with a tank having a diaphragm in the bottom thereof, of means for guiding said diaphragm for parallel movement and counterbalancing the weight of material on said diaphragm, comprising a cylinder, a piston rod extending into said cylinder, a piston in said cylinder carried by said rod, means for oscillating said diaphragm and piston, and
- 10 means for supplying air under pressure to said cylinder to act on said piston.
- 15 3. In a jig, the combination with a frame, of a tank carried thereby, a reciprocable member in said tank, a shaft rigidly attached to said member, a piston on said shaft, a guide for said shaft constructed and arranged to restrict its movement to movement along its own axis comprising a cylinder within which said piston reciprocates, said cylinder having an extended neck 10 carrying a bushing having sliding contact with said shaft, said cylinder being vented to atmosphere on one side of said piston and closed on the other side thereof, means supplying air under pressure to the said cylinder on the closed 15 side of said piston, and means for reciprocating said shaft.

ERNST F. MULLER.
